TOBACCO PRODUCT AND METHOD OF
MANUFACTURE

Walter G. Frankenburg, Millersville, Pa., assignor
to General Cigar Co., Inc., New York, N. Y., a
corporation of New York

No Drawing. Application June 13, 1947,
Serial No. 754,595

14 Claims. (Cl. 131—140)

1

This invention relates to tobacco products adapted for smoking, and more particularly to products comprising tobacco in comminuted form.

The manufacture of cigars has reached a high state of development. Today, even a popular-priced cigar requires the careful blending of as many as fifteen to twenty different types and grades of tobacco. In spite of the great advances which have been made in the design of automatic machines, the making of cigars is still characterized by a large proportion of hand work which limits the rate of production and adds considerably to manufacturing costs. Similar problems arise in the manufacture of cigarettes and pipe tobaccos.

In copending patent application, Serial No. 720,682, of Frankenburg and Garbo, filed January 7, 1947, now abandoned in favor of continuation application, Serial No. 141,357, filed January 30, 1950, now Patent No. 2,592,553, there is disclosed a process for preparing coherent masses of comminuted tobacco by mixing the comminuted tobacco with a limited quantity of an aqueous solution of a water-soluble derivative of cellulose, particularly an ether of cellulose like methyl cellulose or carboxymethyl cellulose, to form a paste which is pressed or rolled into sheets, rods and the like. The thus formed coherent masses of tobacco are then dried and are ready for utilization in cigar-making machines or in any other desired manner. It has been found that these tobacco products tend to be somewhat brittle and to have limited tensile strength. Accordingly, in some cases, as when tobacco sheets prepared by the process of the copending application are fed to a machine utilizing these sheets in the place of the usual binder leaves for cigars, difficulties are encountered in that the sheets frequently tear or rupture and thus interfere with the continuous operation of the machine.

The present invention is in the nature of an improvement of the process and products of the aforementioned copending application.

The primary object of this invention is to produce from comminuted tobacco coherent masses of improved physical properties without impairment of the smoking qualities of the tobacco.

In accordance with this invention, leaf tobacco which has been processed by drying, curing, sweating, fermenting, aging and similar treatments preparatory to its utilization in the manufacture of cigars and like products is comminuted in any of several well-known types of grinders or pulverizers. The tobacco, which may include stems and midribs, is generally ground to such

2

a degree that all of the particles will pass through a 20-mesh screen and a substantial portion will have a particle size corresponding to the openings of a 40-mesh screen. Considerably coarser and finer tobacco powders are, however, utilizable for the purposes of this invention. The comminuted tobacco is then converted into a plastic mass by thoroughly mixing the dry powder with a limited quantity of a highly viscous aqueous solution of a water-soluble derivative of cellulose.

The quantity of aqueous solution of cellulose derivative which is admixed with the powdered tobacco is limited to that which yields a plastic mass having a consistency approximating that of 15 a good neat cement mortar. An excess of solution detectable by the tendency of the plastic mass to exude liquid should be avoided since any substantial loss of liquid reflects a loss of extractable constituents in the tobacco and consequent alteration of the original smoking qualities of the tobacco. Even when soluble constituents are extracted from powdered tobacco with water and the extract is not permitted to become separated from the tobacco paste, impairment 20 of the original properties of the tobacco occurs apparently because the soluble constituents undergo undesirable reactions while in the extract form; the viscous aqueous solutions of cellulose derivatives used in this invention are such 25 poor extracting liquids that the ordinary injury to tobacco from contact with water is largely averted. Usually, one part by weight of comminuted tobacco and about two to six parts by weight of the aqueous solution of cellulose derivative 30 will form a paste of the desired consistency.

The plastic mass of tobacco is rolled out into sheets or otherwise pressed or formed into desired shapes, e. g., extruded as a rod or ribbon. The thus formed coherent mass of tobacco, with or 35 without prior evaporation of the contained water, is treated with any of a wide variety of substances commonly referred to as tannins. It is advantageous to select tannins which are derivatives of pyrogallol or catechol. As known, tannins are 40 extracted from the barks, fruits, woody parts, roots and leaves of many plants such as valonia, myrobalan, oak, chestnut, sumac, quebracho, mimosa, hemlock and catechu. Synthetic tannins which also contain polyhydric phenols as the active ingredients may be used in accordance 45 with this invention.

When the tannin is in finely powdered form it 50 may be applied to the moist surfaces of the formed plastic mass of tobacco by a simple dust-

ing operation. If the tobacco sheet or otherwise shaped mass has already been dried, a solution of the tannin may be sprayed or brushed on the surfaces of the mass.

In order to develop more fully the favorable effect of tannins on coherent masses of tobacco in which a water-soluble cellulose derivative acts as the binding agent it has been found advantageous to expose the tannin-treated mass to a humid atmosphere for a period of at least twelve hours. It is thought that during this period desirable slow reactions between the tannins and ingredients of the tobacco mass as well as perhaps oxidation and polymerization of the tannins occur, and that these reactions lead to the observed improvements in physical properties of the coherent tobacco masses.

After the tannin treatment, the sheet or other coherent form of comminuted tobacco is dried to any desired moisture content. The water is evaporated at moderate temperatures usually not exceeding about 50° C. The resulting coherent, self-supporting tobacco product may then be fed to a cigar-making machine or used in any other desired manner.

From the foregoing description, it is obvious that the tobacco has not lost any of its constituents during processing nor has it been subjected to any harmful conditions, such as water extraction, elevated temperatures or strong acids or bases. Also, the comparatively small additions of extraneous matter entering the tobacco product as binding agent and tannin are surprisingly innocuous to the smoking qualities of the tobacco; as a matter of fact, some tobacco connoisseurs find the tobacco products of this invention milder and pleasanter in smoking than the original tobaccos from which the products are made.

As used in this specification and the appended claims, the term, water-soluble derivative of cellulose, means any water-soluble derivative of cellulose composed solely of carbon, hydrogen and oxygen atoms. Advantageously, such a derivative is of the type represented by the formula:

showing an ether linkage between the cellulose radical and the solubilizing radical. In the formula, n is a number corresponding to the number of cellulose units in the particular cellulose used, x is a number not greater than 3 depending upon the number of hydroxyl groups in the cellulose unit replaced by ether-linked solubilizing radicals and Q is a radical containing 1 to 4 carbon atoms, preferably 2 carbon atoms. Generally, when the radical Q contains 2 or more carbon atoms, the more oxygen atoms there are in the radical Q , the better it is for the purposes of this invention; oxygen present in the form of $—OH$ groups is particularly desirable. Representative water-soluble derivatives of cellulose successfully used in this invention are:

Methyl cellulose— $(C_6H_7O_2(OH))_{3-x} \cdot (O \cdot CH_3)_x$
Carboxymethyl cellulose

$(C_6H_7O_2(OH))_{3-x} \cdot (O \cdot CH_2 \cdot COOH)_x$

Hydroxyethyl cellulose

$(C_6H_7O_2(OH))_{3-x} \cdot (O \cdot CH_2 \cdot CH_2OH)_x$

It is well to note that in the production of certain water-soluble derivatives, for instance, hydroxyethyl cellulose by the reaction between alkali cellulose and ethylene oxide, the reactant furnishing the solubilizing radical to the cellulose may at the same time undergo polymerization

with the result that the cellulose derivative formed may comprise solubilizing radicals which are polymeric in structure. In other words, the radical Q may be composed of a multiplicity of molecular units each containing 1 to 4 carbon atoms in contrast to a single molecular unit, for instance, the single unit $—CH_2 \cdot CH_2OH$ shown above in the formula for hydroxyethyl cellulose. Water-soluble derivatives of cellulose in which the solubilizing radicals have a polymeric structure are useful for the purposes of this invention. Where the water-soluble derivative of cellulose has an acid grouping as in the case of carboxymethyl cellulose, it may be used in the form of the corresponding salt, usually the sodium or potassium salt; the prior statement that the water-soluble derivative of cellulose is composed solely of carbon, hydrogen and oxygen is not intended to exclude the water-soluble salts, e. g., alkali metal salts, of acid-type derivatives of cellulose. At any given temperature and concentration, the viscosity of the aqueous solution of a cellulose derivative will vary with the molecular complexity or weight of its cellulose radical (factor n) as well as with the degree of etherification (factor x). In the foregoing formulae, the factor n is a convenient means used to indicate the polymeric nature of cellulose.

The invention contemplates the use of mixed water-soluble derivatives of cellulose not only in the sense of mixtures of two or more separate and different derivatives but also in the sense of single derivatives having two or more different substituents associated with the cellulose. Thus, in accordance with the first sense, a mixture of equal parts by weight of methyl cellulose and sodium salt of carboxymethyl cellulose may be employed as the binding agent for tobacco products prepared by the process of this invention. In the other sense, suitable binders are high viscosity grades of single, water-soluble cellulose derivatives having two or more different substituents, which may be exemplified by a cellulose derivative of the type of methyl ethyl cellulose or ethyl hydroxyethyl cellulose. It is well to observe that in a water-soluble cellulose derivative with two or more different substituents not all of the substituents need to be substituents or radicals which exert a solubilizing effect on cellulose when dispersed in water. For example, a mixed cellulose ether might have a relatively small proportion of hexyl radicals serving as one substituent and a relatively large proportion of carboxymethyl radicals serving as the solubilizing substituent. In further connection with the though that the cellulose need not be heavily substituted to yield a water-soluble derivative adapted for the purposes of this invention, it is interesting to note that the sodium salt of carboxymethyl cellulose used in the examples presented hereinafter is reported to have only 0.4 to 0.6 carboxymethyl group for each anhydroglucose unit of the cellulose molecule or, in other words, for each cellulose radical of the type formula shown hereinafter.

From the foregoing it is clear that cellulose ethers which are water-soluble and form viscous solutions are particularly useful in this invention. However, the invention is not limited to such ethers and contemplates the use of any suitable water-soluble cellulose derivative, e. g., cellulose esters made up entirely of carbon, hydrogen and oxygen atoms.

The success of the novel tobacco products of this invention are attributable very largely to the use of cellulose derivatives having several critical

properties. An index of suitable water-soluble cellulose derivatives is the viscosity. In general, a suitable cellulose derivative is one yielding a viscosity of at least 1500 centipoises at a temperature of 25° C. when a small quantity thereof not exceeding about 5% by weight is dissolved in water, preferably, the cellulose derivative yields an aqueous solution of equal or greater viscosity when present in only about 2% concentration. These cellulose derivatives not only must dissolve in water and yield at low concentrations highly viscous solutions but also must be capable of forming with the tobacco powder a coherent, tough sheet or mass when their aqueous solutions are evaporated to dryness. The behavior of the cellulose derivative in solution facilitates the preparation of the plastic mass containing the finely divided tobacco as well as the subsequent pressing and shaping of the mass into desired forms. The physical characteristics of the cellulose derivative as deposited from its aqueous solution contribute cohesiveness and flexibility to the tobacco product after it has been dried and conditioned to a desirable moisture content. That properly chosen water-soluble cellulose derivatives should be so effective in producing coherent, self-supporting masses of powdered tobacco is indeed surprising when it is reflected that the finished tobacco product generally contains less than 20% of the cellulose derivative based on the weight of the tobacco, and frequently less than 15%. The preferred tobacco compositions contain about 8% to 15% of admixed cellulose derivative based on the weight of the tobacco.

The smoking compatibility of water-soluble cellulose derivatives and tobacco should be safeguarded by the exercise of care in selecting cellulose derivatives in a state of refinement. The refined products should be free of any appreciable quantities of extraneous matter containing compounds of nitrogen, sulfur, phosphorus and the halogens; in short, compounds giving undesirable products of combustion or of dry distillation should be avoided.

The quantity of tannin required to improve the physical properties of the tobacco sheet or other coherent form varies with several factors including the particular cellulose derivative acting as the binding agent, the particular tannin selected and the degree of improvement desired. In any case, simple trials may be made to determine the optimum quantity of tannin that should be employed. In general, however, the quantity of tannin used will fall within the range of about 50% to 150% by weight of the cellulose derivative in the tobacco product.

Iron and manganese salts may, in some instances, be advantageously added to the tannins in limited proportions, usually from about 0.1% to 2% by weight of the tannins. Such metal salts, particularly the iron and manganese salts of citric acid and other organic acids, appear to promote the favorable reactions and effects of the tannins in the tobacco products of this invention.

It is advantageous to add a small proportion of bentonite or other water-swelling clay to the mixture of tobacco and cellulose derivative. Generally, additions of the order of 1% to 2% by weight of bentonite, based on the weight of dry tobacco powder used, are recommended. It appears that bentonite on swelling in the wet plastic mass of tobacco tends to form a coherent inorganic skeleton or reinforcing network which improves the physical properties of the final product. Tobacco compositions of this invention con-

taining bentonite or like mineral not only are stronger, i. e., show less tendency to crack or crumble, but also exhibit improved smoking characteristics. Moreover, the product burns with a firm, coherent ash. The bentonite tends to adsorb or filter out undesirable tarry constituents and alkaloids of tobacco smoke as it is drawn through the unburned portion of the bentonite-containing tobacco product.

10 It is also sometimes beneficial to use a limited quantity of agar-agar, generally not more than about 5% by weight of the tobacco. It appears that the agar-agar dispersed throughout the mass of comminuted tobacco as a water solution forms a fibrous structure in the finished tobacco product when the water is expelled by evaporation. This belief is based on the observation that agar-agar improves the physical properties of tobacco sheets prepared from finely divided tobacco and a binding agent, e. g., the sodium salt of carboxymethyl cellulose.

15 It is often advisable, where the product of this invention is made in sheet form and is later rolled or bent sharply as in making cigars, that the product contain a plasticizer to increase the flexibility and cracking resistance of the sheet. Additions of glycerine of the order of 2% to 15% by weight, based on the weight of dry tobacco used, to mixtures of comminuted tobacco and aqueous 20 solutions of cellulose derivatives with or without bentonite exert an appreciable plasticizing effect. The presence of glycerine in these amounts in the tobacco product does not lead to the formation of unpleasant or troublesome products of 25 complete or incomplete combustion. In the cigarette industry, glycerine is frequently used as a humectant in the tobacco without adverse effects from the viewpoint of smoking. Sorbitol may be substituted for at least part of the plasticizing 30 glycerine.

35 The water-soluble cellulose derivatives of this invention may also be used in making the highly resilient tobacco sheets or bodies disclosed in another copending application, Serial No. 692,775, 40 of Frankenburg, filed on August 24, 1946, now Patent No. 2,592,554. The latter application teaches that tobacco sheets or like bodies formed from a paste of comminuted tobacco and a viscous aqueous solution of a suitable binder are more 45 resilient and flexible if fine glass fibers are incorporated in the paste. Fine glass fibers of the order of 0.0002" in diameter resembling silk threads not only in appearance but also in softness and flexibility are employed in the proportion of about 1% to 15% based on the weight of the tobacco; preferably, about 2% to 5% by weight of glass fibers are combined with the finely divided tobacco. This invention contemplates 50 the inclusion of glass fibers in the tobacco compositions discussed herein.

55 In the interests of better understanding and greater clarity, illustrative embodiments of the invention are presented hereinbelow in detail. In these examples, which are not to be construed 60 in any restrictive sense, the proportions mentioned are all based on a common weight unit.

Example 1

70 A viscous solution was prepared by dissolving 12 parts of methyl cellulose (Dow Methocel—4000 C. P. S. type) in 500 parts of water. To this solution were added 5 parts of glycerine and 3 parts of sorbitol. Wisconsin cigar leaf tobacco ground to particles chiefly in the size range of 75 20 to 40 mesh was mixed with the solution to

form a consistent paste; 100 parts of the tobacco powder was used. The pasty mass which showed no tendency to exude liquid on standing was placed on a plate of polished stainless steel and covered with a sheet of wax paper. With the aid of a roller, the mass was pressed out between the wax paper and steel plate into a layer about $\frac{1}{60}$ inch thick. The wax paper was removed and the plastic layer was permitted to dry overnight by exposure to room air (about 25° C.). The air-dried tobacco sheet was painted on both sides with an aqueous solution of powdered myrobalan extract, the concentration being 4.0% by weight of total solids or 2.4% of tannins. This treatment introduced 7.2 parts of tannins into the sheet. After drying for 24 hours in room air, the tobacco sheet was found to be appreciably stronger and more flexible than it was before treatment with the tannin solution. Smoking tests revealed that the product had a pleasant aroma and burned satisfactorily.

Example 2

An air-dried tobacco sheet (untanninized) was prepared as described in Example 1. The sheet was sprayed with a liquid quebracho extract which had been diluted with water so that the total solids content was 10% or the tannin content was 6%. The tannin solution penetrated the tobacco sheet so readily that the spraying was applied to only one face of the sheet. The quantity of tannins thus introduced was 16 parts. After drying for 30 hours at room conditions, the tobacco sheet was observed to have improved physical properties when compared with the same sheet without the tannin treatment. The smoking qualities of the tannin-treated tobacco sheet were judged good by tobacco experts.

Example 3

An air-dried tobacco sheet (untanninized) was prepared as described in Example 1. The sheet was sprayed on one side with an aqueous solution containing 5% of wattle extract tannins and 0.05% of manganese citrate. The treated sheet had 12 parts of tannin. By comparative tests, it was shown that the manganese citrate accelerated the tannin reactions so that the sheet could be dried in 10 hours to give a product of the same physical properties obtainable by drying the sheet over a period of 24 hours when the manganese salt is omitted. The finished tobacco sheet of this example passed critical smoking tests.

Tensile strength measurements were made on a plurality of specimens cut from two tobacco sheets of the same composition, thickness, moisture content (25% by weight) and method of preparation except that the tannin treatment had not been given to one of the sheets. Accordingly, the two sheets which had been made substantially as described in Example 1 differed only to the extent that sheet A had been sprayed with an aqueous solution of wattle extract to introduce a tannin content corresponding to 75% by weight of the cellulose derivative in the sheet and sheet B had not been so treated with the tannin solution. The specimens from sheet A had on the average a tensile strength 60% higher than that of the specimens from sheet B.

These measurements were corroborated by practical tests. The sheets were fed to a cigar-making machine which utilized the sheets as the binder leaf in the cigars. During equal operating periods, about 40% of sheet B entering the

machine was wasted by breaks and tears while such failures did not occur with sheet A.

In addition, the cigars made with sheet A as the binder leaf resisted disintegration, when smoked by "cigar-chewers," noticeably better than did cigars containing sheet B as the binder leaf.

It is within the purview of this invention to incorporate, where desired, various additives in the coherent mass of powdered tobacco. Thus, with certain tobaccos which burn with difficulty, there may be admixed minute amounts, say of the order of $\frac{1}{10}$ % of the weight of the powdered tobacco, of combustion catalysts, such as the finely dispersed oxides of iron and other heavy metals. This can be easily achieved either by adding these oxides, preferably in colloidal dispersion, to the aqueous solution of cellulose derivative or by dissolving small amounts of organic salts of iron and other heavy metals in this solution. These salts form the corresponding oxides in a highly dispersed form during the combustion of the smoking product in which they have been incorporated.

In a similar way, organic substances can be added to the aqueous solutions of cellulose derivatives in order to impart a desirable flavor to the smoke of the resulting tobacco product. In all cases, the incorporation and conservation of the additives is greatly facilitated by the fact that they are imbedded in the bulk of the tobacco mass and are not merely adhering to the surfaces of the leaves, as is the case with additives used with leaf tobacco.

Other valuable additives are ingredients which impart light texture and porosity to the tobacco product. For instance, the addition of diatomaceous earth, advantageously in the proportion of 5% to 10% of the weight of the powdered tobacco, results in a material of relatively high porosity and low density. With some tobaccos, this favors combustion and a high aroma content in the smoke.

In preparing the aqueous solution of cellulose derivative with or without additives, it is sometimes advantageous to add small amounts of wetting agents, such as sulfonated long-chain aliphatic acids or their salts. Wetting agents facilitate considerably the attainment of intimate contact and cohesion between the tobacco particles, the additives and the cellulose derivative which may be brought together in accordance with this invention. Generally, the amount of wetting agent which is effective is very small; a desirable range of wetting agent additions covers from 0.01% to 0.10% of the weight of water used in the aqueous solution of cellulose derivative. In such small amounts, the sulfur usually associated with the wetting agent is present in too low a concentration to have any sensible effect; appreciable concentrations are, of course, to be avoided as hereinbefore mentioned.

The present invention is not to be confused with the many suggestions made in prior patents of which a large number issued during the period of 1860 to 1900. These prior proposals generally treated waste tobacco in substantially the same way in which wood, rags, straw, bagasse, etc., are pulped in the manufacture of paper. Some of the later patents acknowledge that the tobacco so converted to paper had lost practically all of the constituents which make tobacco suitable for smoking, and attempted to correct this deficiency by impregnating the tobacco paper with a concentrated decoction obtained by

boiling a suspension of tobacco in water. However, all of these earlier schemes failed because it was not appreciated that tobacco and tobacco extracts are inherently delicate and unstable and that even moderate variations in such factors as temperature and hydrogen-ion concentration may adversely effect the tobacco extracts by causing decomposition, oxidation, polymerization or other chemical reactions of the compounds in tobacco. In contrast to these prior unsuccessful efforts, the present invention involves the mildest conditions of treatment and avoids the pulping of the tobacco in water or other processing liquid which would extract many soluble tobacco compounds and thus leave an impoverished and deteriorated tobacco product.

While the invention is particularly suited for homogeneously blending several tobaccos in a single product, it is still importantly useful in converting even one type or grade of leaf tobacco to a form more uniform in quality and more adapted to mechanical production of cigars and the like. Whether one or several tobaccos are comminuted and made into the products of this invention, the savings in manual labor and tobacco as well as the improvement of smoking properties cannot be overemphasized.

It should be observed that while the products of this invention are made up of comminuted tobacco and a water-soluble cellulose derivative acting as binder, the finished products ultimately have the water-soluble cellulose derivatives in an insolubilized state because of reactions with the tannins and possibly other substances in the coherent tobacco masses. For instance, a tobacco sheet, prepared by mixing powdered tobacco with a viscous aqueous solution of the sodium salt of carboxymethyl cellulose to yield a consistent paste and by rolling the paste out into a thin layer, may be insolubilized by contacting the wet layer with both a tannin and a polyvalent metal salt, e. g., a calcium, aluminum or magnesium salt, and by drying the thus treated layer. It is obvious that, after the tobacco product has been compounded and pressed into the desired form, such insolubilization of the water-soluble cellulose derivative used as the binding agent is not detrimental but rather is beneficial because the binding agent will not be redissolved by the saliva of smokers and will therefore better withstand disintegration of the coherent mass of comminuted tobacco.

Those skilled in the art will visualize many other modifications and variations of the invention set forth hereinabove without departing from its spirit and scope. Accordingly, the claims should not be interpreted in any restrictive sense other than that imposed by the limitations recited within the claims.

What is claimed is:

1. A tobacco product adapted for smoking, which comprises a predominant proportion of dry-ground tobacco, a minor proportion, not exceeding 20% by weight of said tobacco, of a water-soluble cellulose derivative originally having a viscosity of at least 1500 centipoises at a temperature of 25° C. when not more than 2% by weight of said cellulose derivative was dissolved in water, and a minor proportion of a tannin, said cellulose derivative and said tannin functioning to hold the particles of said tobacco together as a coherent mass.

2. The product of claim 1 wherein the water-

soluble cellulose derivative is a cellulose ether of the type represented by the formula:

5 wherein Q is a radical containing 1 to 4 carbon atoms, x is a number not greater than 3 and n is a factor indicating the polymeric nature of cellulose.

10 3 The product of claim 2 wherein the cellulose ether is an alkali metal salt of carboxymethyl cellulose.

4. The product of claim 2 wherein the cellulose ether is methyl cellulose.

15 5. A tobacco product adapted for smoking, which comprises dry ground tobacco, about 8% to 15% of an alkali metal salt of carboxymethyl cellulose, based on the weight of said dry ground tobacco, said salt originally having a viscosity of at least 1500 centipoises at a temperature 20 of 25° C. when not more than 2% by weight of said salt was dissolved in water, and about 50% to 150% of a tannin, based on the weight of said salt, said salt and said tannin functioning to hold said dry ground tobacco as a coherent, 25 self-supporting mass.

30 6. A tobacco product adapted for smoking, which comprises dry ground tobacco, about 8% to 15% of methyl cellulose, based on the weight of said dry ground tobacco, said methyl cellulose 35 originally having a viscosity of at least 1500 centipoises at a temperature of 25° C. when not more than 2% by weight of said methyl cellulose was dissolved in water, and about 50% to 150% of a tannin, based on the weight of said methyl cellulose, said methyl cellulose and said tannin functioning to hold said dry ground tobacco as a coherent, self-supporting mass.

40 7. The improved process of converting tobacco into a physically continuous and coherent form adapted for smoking, which comprises dry-grinding tobacco, mixing the dry-ground tobacco and a viscous aqueous solution of a water-soluble cellulose derivative in proportions to form a cohesive paste substantially free of exudation of 45 said solution, said viscous aqueous solution having a viscosity of at least 1500 centipoises at a temperature of 25° C., shaping said paste, treating the shaped paste with a tannin, and drying said shaped and treated paste into a physically 50 continuous and coherent form adapted for smoking.

55 8. The process of claim 7 wherein the water-soluble cellulose derivative is a cellulose ether of the type represented by the formula:

wherein Q is a radical containing 1 to 4 carbon atoms, x is a number not greater than 3 and n is a factor indicating the polymeric nature of 60 cellulose.

65 9. The process of claim 7 wherein the water-soluble cellulose derivative is an alkali metal salt of carboxymethyl cellulose.

10. The process of claim 7 wherein the water-soluble cellulose derivative is methyl cellulose.

11. In the manufacture of smoking products, the improvement which comprises dry grinding tobacco, mixing dry-ground tobacco with a quantity of a viscous aqueous solution of a water-soluble cellulose derivative sufficient to form a cohesive paste but insufficient to permit exudation of said solution from said paste, said viscous aqueous solution having a viscosity of at least 1500 centipoises at a temperature of 25° C., pressing 70 said paste into a thin layer, applying a tan-

nin to the surface of said layer, and drying said layer to a coherent sheet.

12. The process of claim 11 wherein the water-soluble cellulose derivative is sodium carboxymethyl cellulose.

13. The process of claim 11 wherein the water-soluble cellulose derivative is methyl cellulose.

14. In the manufacture of smoking products, the improvement which comprises preparing a cohesive and substantially non-exuding paste comprising dry-ground tobacco, not more than about 15% of a water-soluble cellulose derivative based on the weight of said tobacco, and water, said cellulose derivative and water forming an aqueous solution having a viscosity of at least 1500 centipoises at a temperature of 25° C. shaping said paste, treating said shaped paste with a tannin, and evaporating water from said shaped and treated paste to leave a coherent form of said tobacco.
